CLAIM

The ornamental design for a perfume bottle, as shown and described.

DESCRIPTION

FIG. 1 is a front view of a perfume bottle showing my new design;

FIG. 2 is a top view thereof;

FIG. 3 is a rear view thereof;

FIG. 4 is a right side view thereof; and,

FIG. 5 is a left side view thereof.

The broken lines showing on the perfume bottle are included for the purpose of illustrating only and form no part of the claimed design.

The bottom view is unornamented and forms no part of the claimed design.
